UNITED STATES PATENT OFFICE.

WILLIAM F. STREICH, OF PHILADELPHIA, PENNSYLVANIA.

SUPPORT AND BRACE FOR TABLE LEGS.

Application filed July 13, 1921. Serial No. 484,431.

To all whom it may concern:

Be it known that I, WILLIAM F. STREICH, a citizen of the United States, and resident of Philadelphia, county of Philadelphia, 5 State of Pennsylvania, have invented certain new and useful Improvements in Supports and Braces for Table Legs, of which the following is a specification.

This invention relates to a combined table 10 and transportation base for office accessories and constitutes an improvement relating to the type of device set forth in my Patent No. 1,360,052, granted Nov. 23, 1920. It relates particularly to the novel structural 15 arrangement by which the table legs and their sockets cooperate when the legs enter the socket to support the table top, and also when they are secured in place along the under surface of the table top for trans- 20 portation, and means for strengthening and steadyng the parts when assembled for transportation, whereby the accessories secured thereto will be held more securely; but it also includes other novel features which 25 will be more fully understood from the following description and claims taken with the accompanying drawings.

In the drawings:

Figure 1 is a transverse section through 30 the table top looking towards the end legs which are in place but partly broken away.

Figure 2 is a longitudinal section through the table top, bottom side up, the facing leg brackets forming the sockets and the legs 35 secured in place along the lower surface of the table top ready for transportation.

Figure 3 is an enlarged vertical section on the line 3—3, Figure 1, longitudinally of the table through a corner leg bracket and a 40 leg therein partly broken away.

Figure 4 is a cross section of the bracket and leg in operative relation, taken on the line 4—4 of Fig. 1.

Figure 5 is a cross section on the line 5—5 45 of Figure 2 with the table top broken away at the sides.

Figure 6 is a perspective view of one of the leg brackets or sockets, the adjacent portion of the top being shown in dotted lines.

Figure 7 is a perspective view of the upper 50 end of a leg which enters and engages the socket.

Figure 8 is a perspective view of the table, bottom side up, and its parts, the legs being 55 removed.

Figure 9 is a face view of a metal blank

cut to form for making a corner leg holding bracket or socket.

Figure 10 is a similar view of the blank shape of the upper end of a leg before it is 60 bent to form; and

Figure 11 is a fragmentary perspective view of a modified form of the means on the bottom of the table for receiving the legs when ready for transportation, strengthen- 65 ing the connection.

Fig. 12 is a cross section through the legs and strengthening bar in folded position on the under surface of the table and also the adjacent portions of the table and support- 70 ing bars showing the preferred structure and method of folding the legs and attached parts;

Fig. 13 is a section on the line 13—13 of Figure 12;

Fig. 14 is a perspective view of the upper 75 end or socket section of a table leg made of wood having therein a sheet metal socket of the general type shown in Figure 2;

Fig. 15 is a perspective view of the upper 80 end of a wooden table leg having a reduced portion carrying a sheet metal extension having a form similar to that shown in Figure 7 adapted to enter and engage the socket shown in Figure 14; and

Fig. 16 is a back view of the parts shown 85 in Figures 14 and 15 in operative engage- ment.

In the embodiment of the invention shown for purposes of illustration, the table top 90 10 may be made of wood or any other suitable material, and as set forth in my prior patent above mentioned is made of such size and shape as to be inserted in a trunk or travelling case by a sliding action like a 95 drawer.

Four sheet metal brackets 11 forming leg sockets are secured to the under sur- 100 face of the table near the corners and the upper ends of the legs 12 fit in said sockets and in operative position extend downward at right angles to the table top and are re- 105 leasably held in position by interengaging parts of said bracket and upper end of the leg. Each bracket is formed of a single piece of sheet metal cut and bent to shape, and the socket thus formed is rectangular in section and has an open end to receive the lug and one open side being channel shaped in section. Its specific form is shown in Figure 6, and the sheet metal blank from which 110 it is made is shown in Figure 9. It includes the vertical back portion 13 constituting the

base portion of the channel which has considerable width, and the side portions 14 and 15 of less width at right angles to the back portion, and each portion has an integral flange 16 bent outwardly at its upper edge to fit against the under surface of the table top and each flange is perforated to permit the use of screws to rigidly fasten it to the top. The brackets are so arranged that the open side of the socket in one faces the open side of the corresponding socket at the other end of the table, so that there are a pair of sockets on each side of the table facing each other longitudinally of the table, for a purpose later described. The back or base portion 13 is cut on vertical parallel lines 17, 18, from the inner edge of flange 16 at the top line for a short distance and then on V-shaped lines 19 and 20 down to a rectangular extension 21, notches 22, 23 being cut at the point where the parallel lines join the V-shaped lines. The lower end of the tongue or flap thus produced is cut off on the line 24, and the material along the edges 19 and 20 is folded inward on lines at the bottom of notches 22, 23, parallel to those edges leaving inclined groove like recesses between the folded edges and the back portion 13 having a width substantially equal to the thickness of the metal of the leg forming the inclined parts 25 and 26 shown in Figure 6 for interlocking with a portion of the leg by a tongue and groove connection. The tongue or flap is bent inwardly at right angles to the back portion on the line 27 at its upper end, and then downwardly at right angles on the line 28, forming a top ledge or abutment 29 and a downwardly extending interlocking flange 30 spaced inwardly from the plane of back portion 13 a sufficient distance to permit the end wall of the leg to pass in behind it when the leg is in folded position as herein-after explained.

The legs 12 are made of sheet metal and are channel shaped in section with the base of the channel much wider than the sides, and they are of such size in section as to fit the inner surfaces of the base 13 and end wall 14 and 15 of a bracket, or, in other words, to closely fit in the socket when in position to support the table. Each leg is made of a single piece of sheet metal and bent to shape, the form of the blank at the upper end being shown in Figure 10 and the finished upper end of the leg being shown in Figure 7. In forming the leg from the blank shown in Figure 10, the sides of the blank are bent to positions at right angles to the center portion on the parallel longitudinal dotted lines 31 and 32, but before the bending the material at the end between the sides is cut away on the lines shown. This leaves parallel side strip extensions 33 and 34, the inner edges of which are parallel to the fold lines 31, 32, but slightly nearer the margins of the blank. On the inner facing of each of these side strips or tabs near the bottom a laterally extending section of material is left having a straight line horizontal top and a straight line inner edge extending down to the dotted line 35 where the extensions or tabs 33 and 34 are bent at right angles to the body of the blank as later explained. This inwardly extending section of the material is cut outwardly on the fold line 35, beyond the fold lines 31 and 32 a distance equal to the thickness of the metal leaving inwardly projecting tabs 36, 37. At points inwardly of the fold lines 31 and 32 a distance substantially equal to the height of tabs 36-37 the material is removed between vertical parallel lines 38-39 and then between inwardly inclined lines 40-41, making a V-shaped opening or vacant space corresponding in shape and size to that heretofore described as formed in the leg bracket. At the bottom of the V there is an integral upwardly extending straight sided strip of metal 42. In shaping the leg and its upper end from this blank, the sides including the extensions 33 and 34 are bent inwardly at right angles to the center portion on the lines 31, 32, making the leg channel shaped in section. The tabs 36 and 37 are bent at 90 right angles to extensions 33, 34 on the lines parallel to lines 31 and 32 but on the outer side thereof a distance equal to the thickness of the blank. The extensions 33 and 34 are then bent inwardly towards each other on 95 the line 35 until they are in horizontal position with their ends slightly lapping, forming the end wall 43 of the leg and with the tabs 36 and 37 fitting against the inner face of the central portion of the leg out to the 100 lines 38 and 39. The overlapping ends of extensions 33, 34, may be brazed or welded together and it will be noted that the rear margin of the top wall 43 of the leg between the end lines 38 and 39 of the cutaway portion is set inwardly, leaving an opening at the edge of the end wall. The upwardly extending strip 42 is bent rearwardly or outwardly from the rear wall of the leg and then upwardly at right angles, as shown in 110 Figure 7, thus forming a projecting spring or snap catch with a straight edge lower contact shoulder 44. The leg thus formed has the center or back portion 45 and the sides 46, 47, and is channel shaped in section, and thus constitutes a channel bar. In inserting the upper end of the leg in the socket to sustain the table, it is moved in endwise with its sides in contact with sides 14 and 15 of the bracket and its back portion 125 in contact with the rear wall 13 of the bracket and in this movement the V-shaped upper edges 40 and 41 of the back portion 45 will pass under the edges of flanges 25, 26 in the slots which will lock them against 130

outward movement, and because of the tapering contact the weight of the table and articles on it will tend to tighten and strengthen the connection by a wedging action. During this upward movement of the leg in the socket, the spring locking catch 42 will be depressed by contact with the rear wall 13 of the bracket until it reaches the open extension 21, when it will snap outward with its downwardly facing contact shoulder 44 above the bottom edge of said opening, thus automatically locking the leg against longitudinal removal. The cutaway portion of the end wall 43 between 15 38 and 39 is sufficient to permit it to pass up along the outer side of flange 30 of the socket. The strength and fit of the flanges 25 and 26 are such that the leg can not accidentally be turned outward to release catch 20 42 from engagement, but in order to effect that release, the catch itself must be depressed. This structure furnishes very simple and efficient means for easily and quickly securing the legs to the table in operative 25 position and for removing them when desired.

Another important phase of the invention relates to the structure and combination of parts whereby the parts of the table 30 and other articles may be brought together in compact, convenient form for transportation, and whereby they will be sustained in proper position and relation so securely and strongly as to avoid possible damage or accident in transportation. To this end, the two facing legs on one side of the table are made of different sizes in their channel shaped section, whereby one may fit within the other longitudinally, and it follows of 35 course that the brackets or sockets for those legs differ correspondingly in sectional size but otherwise all legs and all sockets are alike. In preparing for transportation the legs are removed from their sockets in pairs 40 and together with strengthening means in the form of a filler preferably consisting of a bar of wood or other similar material of such size and shape as to fit in and fill the channel in the smaller leg are folded together closely fitting longitudinally and are bolted to the table top on the line between 45 the sockets from which the legs were taken and cross bars for carrying various office accessories are placed across the folded legs 50 and held in place by the same bolts which secure the folded legs to the table top. The preferred structure of the legs and bar for use in folding and the preferred arrangement of parts when folded are shown in 55 Figures 12 and 13, but since Figures 2 and 8 more clearly and completely show the arrangement of parts when folded for transportation we will in the interest of clearness first describe the operation with reference to them.

The legs of a pair are removed from their sockets and a bar 50 of wood or similar material is placed in and along the channel of the smaller leg 52 and it closely fits that channel and extends to points near its ends, 70 as shown in Figure 2. In this form or arrangement the open side of the channel faces downward towards the table, the bar 50 resting on the table and the other larger leg 53 fitting over and laterally embracing the 75 smaller leg 52 with its open channel side also facing the table. In bringing the legs together in this way their ends which when vertical to support the table entered the sockets longitudinally now are horizontal 80 and enter the sockets laterally through their open sides and the end wall 43 of each leg passes down behind the flange 30 of the socket thus interlocking the parts against end movement and the sides of the sockets 85 prevent lateral movement as shown in Figure 2. A series of bolts 54 having countersunk heads in the table top pass through corresponding openings in the table, bar 50, and legs 52-53 and by means of thumb nuts 90 securely and rigidly clamp and hold the parts in position. The closely fitting bar or strip 50 serves to protect the bolts and as a strengthening and steadyng means and prevents looseness and thereby affords the resiliency necessary to prevent damage from violent jars in transportation, and this is important in devices of this kind because of the peculiar strains to which the parts are subjected. Cross bars or supporting strips 100 55 are secured across two pairs of folded legs by the bolts 54 heretofore mentioned as shown in Figures 2 and 5 and these bars carry various office engineering or other accessories secured to them such as typewriters, calculating machines, machine models and surveying instruments.

In the preferred form shown in Figures 12 and 13 the leg 52 made of the smaller channel bar is placed along the surface of 110 the table open side up, the bar 50 is then placed in it as in Figures 2 and 5 except that the reversal of the position of the leg leaves its upper face exposed. The leg 53 made of the larger channel bar is thus 115 placed over the first leg and bar with its sides extending approximately to the surface of the table. In this form in order to supply additional means for holding the cross bars 55 securely in position the bottom wall and adjacent portions of the sides of leg 53 are pressed inwardly at 57 forming a depression or socket having a depth and length substantially equal to the thickness and width of bar 55 whereby said bar 120 may enter it and be prevented from side movement by contact with the walls at the ends of the recess. The top edges of the sides of leg 52 are cut away to form notches 125 of such size as to receive the depressed por- 130

tions of leg 52 and the upper surface of bar 50 is similarly cut away for the same purpose. The bolts 54 pass through all the parts as in the form shown in Figures 2 and 5 and the folded parts are arranged on the table surface in the same way with the ends of the legs in their sockets and their end walls 43 interlock with flange 30 of the socket. It will be noted by reference to 10 Figure 7 that the cut away portion of the base 45 of the leg channel at its end permits the flange 30 on the socket to pass into the channel when the end of the channel is lowered into the socket closed side down. It 15 will be noted that in this form the two channel bars constituting the legs entirely surround the bar and enclose it laterally and are in close contact with it on all sides one surface being in contact with the bottom wall of leg 53 and the other three in contact with the three inner surfaces of leg 52. This with the socket connection to the cross bars produces a very strong supporting means having all of the resiliency necessary to the best results.

Instead of using a continuous strengthening bar 50 as heretofore stated I may use a series of strengthening blocks 56 shown resting on the table top in Figure 11. They 20 are placed in the smaller leg in folding just as the bar is except that one is preferably placed at each point where a bolt 54 passes through and it passes through an opening through the block.

Figures 14, 15 and 16 illustrate a structure in which the channel iron automatically acting and locking connection between the leg and socket substantially as heretofore described is applied to the wooden legs 40 of tables. In the form shown the wooden leg 58 is reduced in size on three sides at its upper end producing an extension rectangular in section with one face flush with one face of the leg and the other three offset inwardly from the faces forming a shoulder 59. This extension is of such size as to fit 45 in the lower end of a channel iron sheet metal construction 60 such as illustrated in Figure 7 heretofore described, the relative 50 lengths of the extension and sheet metal sections being such that the top of the extension will be below the snap hook 44 as illustrated in Figure 15 in dotted lines. Screws or other fastening means 61 may 55 pass through member 60 and secure it in place on the extension. A short wooden member 62 corresponding generally in section to the upper end of leg 58 but having a longitudinal channel 63 in one face of such 60 size as to receive a sheet metal leg socket 64 corresponding to the form shown in Figure 6 and heretofore described except that the top flanges 16 are omitted. This sheet metal socket is securely fastened in place in 65 the channel groove 63 by suitable means and

the wash socket member is secured at its upper end Figure 14 to the under surface of the table by any suitable known means. The wooden leg and wooden socket are brought together in the same way as heretofore described in connection with the all metal parts of Figures 6 and 7 and having substantially the same sheet metal parts they will automatically interlock in the same way as do the parts shown in Figures 70 6 and 7. In order to release the automatic catch 44, illustrated most clearly in Figure 7, and permit the leg to be withdrawn from the socket a hole 65 is bored in member 62 in line with that catch so that an implement 75 may pass through the opening and press the catch inward out of engagement with the edge 21 of the metal socket.

The shoulder 59 on the leg will fit against the lower end of the wood member 62 when 80 the leg is in operative position and the outer surfaces of the leg and member will be in the same continuous planes thus producing a neat appearance.

It will of course be understood that the 85 invention is not limited to the structural details of the embodiments shown for purposes of illustration beyond what is defined in the claims.

Having thus described the invention, 90 what is claimed as new and desired to be secured by Letters Patent is:

1. In a device of the class described, the combination with a table top of a socket open at its outer end and on one side secured thereto, a leg so formed as to enter said socket through its open end and to fit the inner portion of said socket laterally, interengaging cooperating means on the adjacent parts of said socket and leg so arranged as 100 to come into operative relation and prevent lateral movement of said leg in said socket out through the open side thereof by and through the inward movement of the leg into the socket a predetermined distance, 105 and an automatic catch for then locking the leg to the socket against longitudinal outward movement.

2. In a device of the class described, the combination with a table top of a sheet 115 metal bracket, channel shaped in section, secured at one end to said top and projecting therefrom forming a leg receiving socket, a sheet metal table leg of channel form in section entering longitudinally and fitting said socket, means on the fitting base portions of said bracket and leg to lock the leg in said socket against outward movement through its open side embodying parts of the metal of which these portions are formed projecting therefrom on the facing sides and each projection on one portion being adapted to enter openings in the other portion and operatively engage that portion at a predetermined point of the inward movement of the 120 125 130

leg in the socket with its base in contact with the base of the socket.

3. In a device of the class described, the combination with a table top of a sheet metal bracket, channel shaped in section, secured at one end to said top and projecting therefrom forming a leg receiving socket, a sheet metal table leg of channel form in section entering longitudinally and fitting said socket, means on the fitting base portions of said bracket and leg to lock the leg in said socket against outward movement through its open side and to automatically but releasably lock it against longitudinal withdrawal, embodying parts of the metal of which these portions are formed projecting therefrom on the facing sides and each projection on one portion being adapted to enter openings in the other portion and operatively engage that portion at a predetermined point of the inward movement of the leg in the socket with its base in contact with the base of the socket.

4. In a device of the class described, the combination with a sheet metal bracket channel shaped in cross section of such length as to constitute a leg socket with an open end and an open side, of a sheet metal leg channel shaped in cross section of such size as to longitudinally enter the open end of said socket and closely fit it with its base portion in contact with the base portion of said socket, tongue and groove interengaging parts formed on and from said base portions of said leg and socket so constructed and related that they will interlock and prevent said leg from moving out through the open side of said socket by and through a predetermined longitudinal movement of said leg in said socket.

5. In a device of the class described, the combination with a sheet metal bracket channel shaped in cross section of such length as to constitute a leg socket with an open end and one open side of a sheet metal leg channel shaped in cross section of such size as to longitudinally enter the open end of said socket and closely fit it with its base portion in contact with the base portion of said socket, tongue and groove interengaging parts formed on and from said base portions of said leg and socket so constructed and related that they will interlock and prevent said leg from moving out through the open side of said socket by and through a predetermined longitudinal movement of said leg in said socket, the interengaging parts being so related or inclined to each other and the line of movement as to cause a wedging action.

6. In a device of the class described, the combination with a sheet metal bracket channel shaped in cross section of such length as to constitute a leg socket with an open end and one open side, of a sheet metal

leg channel shaped in cross section of such size as to longitudinally enter the open end of said socket and closely fit it with its base portion in contact with the base portion of said socket, tongue and groove interengaging parts formed on and from said base portions of said leg and socket so constructed and related that they will interlock and prevent said leg from moving out through the open side of said socket by and through a predetermined longitudinal movement of said leg in said socket, and a releasable catch on one portion so constructed as to automatically extend across a rearwardly facing part on the line of its movement of the other portion, thus locking the leg in the socket against being withdrawn longitudinally.

7. In a device of the class described, the combination with a sheet metal bracket channel shaped in cross section of such length as to constitute a leg socket with an open end and one open side, the base portion of the channel being cut away throughout its central portion at one end leaving facing edges extending downwardly from that end at an incline to each other in V form with a short transverse straight edge at the bottom, the material along the edges of the V being bent inwardly of the socket to a position substantially parallel to the base of the socket but spaced therefrom a predetermined distance forming branching grooves, and a sheet metal leg channel shaped in cross section adapted to enter longitudinally and closely fit said socket with its channel base portion in contact with the base portion of the socket, the central portion of the channel base of said leg at its end being cut away leaving facing edges inclined towards each other in V form adapted to enter and fit the recesses formed by the bent over edges in the base portion of the socket bracket.

8. In a device of the class described, the combination with a sheet metal bracket channel shaped in cross section of such length as to constitute a leg socket with an open end and one open side the base portion of the channel being cut away throughout its central portion at one end leaving facing edges extending downwardly from that end at an incline to each other in V form with a short transverse straight edge at the bottom, the material along the edges of the V being bent inwardly of the socket to a position substantially parallel to the base of the socket but spaced therefrom a predetermined distance forming branching grooves, and a sheet metal leg channel shaped in cross section adapted to enter longitudinally and closely fit said socket with its channel base portion in contact with the base portion of the socket, the central portion of the channel base of said leg at its end being cut away leaving facing edges

- inclined towards each other in V form cured to the under side thereof near the corners, each having an open side facing the corresponding socket at the opposite end of the table, legs in the form of channel bars so constructed as to detachably fit in and engage said sockets to support the table when in upright position and each pair of legs for a pair of facing sockets being of such form and relative size that one of those legs may in folded position lie with its open side up along the surface of the table in the line of the facing socket with one end extending into and laterally fitting its socket through the open side thereof, and the other leg of the pair may be folded to closely fit over and on said first mentioned leg with its end extending into and laterally fitting its socket, cooperating means on said legs and in said sockets preventing said legs from moving longitudinally out of said sockets when folded, and releasable means for securely fastening said legs to said top in folded position.
9. In a device of the class described, the combination with a sheet metal bracket channel shaped in section forming a leg socket having an open end and one open side, laterally extending flanges at one end for securing it to a table, a flange of substantial width cut from the base portion or wall of said channel between its edges at said end and integrally connected along one edge to the end flange between its ends bent inwardly of the socket a fixed distance at its connecting edge and then downwardly parallel to the base wall of the socket, and a sheet metal leg channel shaped in section of such size and shape as to fit and engage said socket when inserted longitudinally and having an end wall connecting the sides adapted to enter behind the downwardly extending flange in the base portion of the socket channel and thus lock the leg against longitudinal movement when it is in folded position along the under surface of the table with its end extending into said socket from the open side, the edge of the end wall at the back being cut away between its ends sufficiently to permit the leg to move upwardly in the socket in upright position without interference from said downwardly extending flange in the socket.
10. In a device of the class described, the combination with a table top, of sockets secured to the under side thereof near the corners, each having an open side facing the corresponding socket at the opposite end of the table, legs in the form of channel bars so constructed as to detachably fit in and engage said sockets to support the table when in upright position, and each pair of legs for a pair of facing sockets being of such form and relative size that one of those legs may in folded position lie with its open side either up or down along the surface of the table in the line of the facing socket with one end extending into and fitting laterally its socket through the open side thereof and the other leg of the pair may be folded to closely fit over and on said first mentioned leg with its end extending into its socket and releasable means for securely fastening said legs to said top in folded position.
11. In a device of the class described, the combination with a table top, of sockets se-

- base portion from the bottom of the socket towards the open end spaced therefrom sufficiently to permit the end wall of the leg to enter behind it when the leg is 5 folded against the table surface with its end in the sockets, the cross sectional size of the facing sockets of each pair and of the legs for those sockets being such that one leg will fold on and over the other, fitting it 10 closely transversely, and means for rigidly securing said legs in folded position to the table top and for securing across them means for attaching other articles in fixed position.
14. In a device of the class described, the combination with a table top, of leg sockets near the corners, two pairs of legs, channel shaped in section, each pair adapted to detachably enter longitudinally and engage 15 the sockets along one side of the table and to be folded together one closely fitting over and on the other along the surface of the 20 table in the line of the sockets, strengthening and steady means so shaped as to closely fit transversely in the channel of the inner leg when folded, and means for rigidly securing and clamping together said folded legs, strengthening and steady means, and table top.
15. In a device of the class described, the combination with a table top, of leg sockets near the corners, two pairs of legs, channel shaped in section, each pair adapted to detachably enter longitudinally and engage 25 the sockets along one side of the table and to be folded together one closely fitting over and on the other along the surface of the table in the line of the sockets, strengthening and steady means so shaped as to 30 closely fit transversely in the channel of the inner leg when folded, and means for rigidly securing and clamping together said folded legs, strengthening and steady means, and table top.
16. In a device of the class described, the combination with a table top, of leg sockets near the corners, two pairs of legs, channel shaped in section, each pair adapted to detachably enter longitudinally and engage 35 the sockets along one side of the table and to be folded together one closely fitting over and on the other along the surface of the table in the line of the sockets, strengthening and steady means consisting of a bar 40 having a length slightly less than the distance between facing sockets of a pair so shaped as to closely fit transversely in the channel of the inner leg when folded and means for rigidly securing and clamping together 45 said folded legs, strengthening and steady means, and table top.
17. In a device of the class described, the combination with a table top, of leg sockets near the corners, two pairs of legs, channel shaped in section, each pair adapted to detachably enter longitudinally and engage the 50 sockets along one side of the table and to be folded together one closely fitting over and on the other along the surface of the table in the line of the sockets, strengthening and steady means so shaped as to closely fit transversely in the channel of the inner leg when folded and means for rigidly securing and clamping together said folded legs, strengthening and steady means, and table top.
18. A folding table comprising a top, leg sockets secured thereto, legs adapted to enter said sockets longitudinally to support the table and to enter them laterally when in folded position parallel to the table, cooperating means on said legs and sockets for automatically but releasably locking the 55 legs in the sockets against longitudinal or lateral movement when inserted longitudinally and cooperating means at the end of said legs and bottoms of said sockets for automatically locking the ends of the legs 60 in said sockets against side movement or end movement when the legs are folded with their ends in the sockets.
19. In a device of the class described the combination with a table top of a pair of 65 channel-shaped legs therefor one closely fitting within the longitudinal channel of the other with its open side edges at the bottom of the channel and its base portion closing the open side of said other channel leg, thus 70 forming in effect a laterally enclosed chamber rectangular in section, a strengthening bar of wood in and substantially filling the space in said chamber between said legs 75 with its surfaces in contact with the inner 80 facing surfaces of said leg channels and extending throughout the major portion of their length, releasable means clamping said legs together on said bar and to the table 85 top with the base of one of said channel 90 legs in surface contact with the table top and sockets on said top for said legs.
20. In a device of the class described the combination with a table top of a pair of 95 channel-shaped legs therefor one closely fitting within the longitudinal channel of the other with its open side edges at the bottom of the channel and its base portion closing the open side of said other channel 100 leg, thus forming in effect a laterally enclosed chamber rectangular in section, a strengthening bar of wood in and substantially filling the space in said chamber between said legs with its surfaces in contact 105 with the inner facing surfaces of said leg 110

channels and extending throughout the major portion of their length, the base portion of the channel forming one leg and the adjacent portion of the sides being depressed at fixed intervals longitudinally forming transverse grooves or depressions on the outer surface, corresponding parts of the bar and sides of the other leg being removed to make room for and fit the depressed portion, supporting bars at right angles to said folded legs fitting in said grooves or notches, and bolts having heads countersunk in said top passing through said top, through the base of the channel of one leg which is in close surface contact with the table top, through the bar, through the depressed portion, other leg and through the supporting bar in the depression and having screw threaded nuts clamping the parts together.

21. In a device of the class described the combination with a table top of a pair of facing channel-shaped leg sockets of different sizes in section secured to said top near its ends, a channel-shaped leg on said top with one end entering from the open side and fitting the socket of smaller size and extending therefrom towards the other socket the open side of the channel facing outward from the top, a strengthening and steadyng bar fitting in and substantially filling the channel of said leg from a point near one end to a point near the other end, a second channel-shaped leg of larger sectional size than the first leg, closely fitting over and laterally enclosing said first leg and bar longitudinally with one face of said bar in contact with the base portion of its channel, one end of said second leg fitting in its socket, bolts having countersunk heads in said top passing through said top, legs and bar and having screw threaded nuts for clamping them together.

22. In a device of the class described,

the combination with a table top, of leg 45 sockets near the corners, two pairs of legs, channel shaped in section, each pair adapted to detachably enter longitudinally and engage the sockets along one side of the table and to be folded together one closely fitting 50 ever and on the other along the surface of the table in the line of the sockets with the base of the channel of the inner leg in surface contact with the table top, a strengthening bar laterally enclosed by said folded 55 legs and closely fitting therein, the base of the outer bar of both folded pairs having notches at intervals the said notches being transversely aligned on the two pairs, supporting bars extending across both folded 60 pairs each resting in a pair of aligned notches and screw thread bolts for each pair passing through and clamping together said table top, two legs and supporting bars.

23. In a device of the class described, the 65 combination with a table top of a leg bracket secured thereto having a socket open at one side and embodying a channel shaped sheet metal member, a table leg having a channel shaped sheet metal part at its upper 70 end entering longitudinally and fitting said channel shaped sheet metal socket member, means on the fitting base portions of the channels of said bracket and leg to lock the leg in said socket against outward movement through its open side embodying parts of the metal of which these portions are formed projecting therefrom on the facing 75 sides and each projection on one portion being adapted to enter openings in the other 80 portion and operatively engage that portion at a predetermined point of the inward movement of the leg in the socket with its base in contact with the base of the socket.

In testimony whereof I hereunto affix my 85 signature.

WILLIAM F. STREICH.
